(57) **CLAIM**

The ornamental design for a fingerprint door lock, as shown and described.

DESCRIPTION

FIG. 1 is a perspective view of a first component of a fingerprint door lock showing my new design, the second component thereof not shown for clarity of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second component of the fingerprint door lock showing my new design, the first component thereof not shown for clarity of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the fingerprint door lock including the first and second components.

The broken lines in the drawings depict portions of the fingerprint door lock that form no part of the claimed design.
